PORTABLE OUTDOOR GRILL

Rudy Ratcliff, 120 S. State (Bank Bldg.),
Marengo, Ill. 60152

Filed June 21, 1966, Ser. No. 2,766

Term of patent 14 years

(Cl. D81—10)

FIG. 1 is a perspective view of a portable outdoor grill showing my new design;

FIG. 2 is another perspective view of said grill taken from another angle;

FIG. 3 is a plan view; and

FIG. 4 is a front end view.

The utensils shown in broken lines in FIGS. 1, 3 and 4 are included for illustrative purposes only.

I claim:

The ornamental design for a portable outdoor grill, substantially as shown and described.
